UNITED STATES PATENT OFFICE.

JOHN BLYTH, OF CHICAGO, ILLINOIS, ASSIGNOR TO EASTMAN KODAK COMPANY, OF ROCHESTER, NEW YORK, A CORPORATION OF NEW YORK.

EASEL FOLDER FOR PHOTOGRAPHS.

Application filed June 24, 1926. Serial No. 118,207.

This invention relates to photography, and more particularly to easel folders for photographs which may also be used as a picture stand. One object of my invention is to provide a satisfactory latch for holding the mount in an erect or picture displaying position. Another object is to form such a latch in which the latching parts are integral with the flaps from which they are made. Another object is to provide a resilient member which constantly tends to force and retain the parts in a latching position, and a resilient member which may be readily released for withdrawing the parts from such a latching position; and other objects will appear from the following specification, the novel features being pointed out in the claim at the end thereof.

In the drawing in which like reference characters denote like parts throughout:

Fig. 1 is a perspective view of an easel folder constructed in accordance with and embodying one form of my invention;

Fig. 2 is an enlarged fragmentary rear elevation of a portion of the folder shown in Fig. 1;

Fig. 3 is an enlarged fragmentary view partially in section of the latch structure; and

Fig. 4 is a section on line 4—4 of Fig. 3.

A preferred embodiment of my invention consists in a front picture carrying member 1, which may be provided with the usual type of corner pockets 2 by which a picture 3 may be attached to this member. While I have shown the surface 4 surrounding the photograph plane, this area is usually provided with a fancy border which may consist of a plurality of mounting sheets, embossing, printed areas, or other desired decorative features.

The front member 1 carries a pair of flaps 5 and 6 which are preferably integral with the front 1, and are adapted to be folded across lines 7 and 8. Flap 5 is preferably somewhat shorter than the front member 1, and is provided with an edge 9 which is adapted to rest upon a supporting surface when the flaps are, as shown in Fig. 1, in a picture exhibiting position.

Flap 6 is preferably considerably shorter than flap 5, and may have a tapered end terminating in an ear 11 which is preferably equipped with latching walls 12. As best shown in Fig. 4, the latching walls are of

hook-like formation, and are adapted to engage in an aperture 13 cut in the flap 5.

The aperture 13 may be provided by punching out side walls 14 and a bottom wall 15 from the material of which flap 5 is made. Across the top of the opening 13 the material is preferably formed with a tool, as at 16, so as to form a resilient hinge by which a tab 17 is connected to the flap 5.

The shape of the cut forming the side walls 14 and the bottom walls 15 is not material, except that the walls 14 should be spaced further apart at one location than at another so that ear 11 may be entered at a wide part and may engage a narrow part. I prefer to form the wide part above the narrow part, as shown in the drawings.

The tab 17 has two functions,—first, when the picture support is used as a folder the tab 17 fills up the opening 13 so that the opening is less noticeable, and the flap 5 forms a smooth unbroken covering for the picture 3. Second, the tab 17 forms a resilient member tending to press and hold the ear 11 in a latching position. When ear 11 is thrust between a widely spaced portion of the walls 14 the tab 17 tends to thrust downwardly upon the ear 11, moving the hook-like walls 12 into engagement with the narrow portion of the walls 14, thus latching flaps 5 and 6 in a position in which the front will form an easel for exhibiting the picture.

The natural tendency of the tab 17 to move toward the plane of the flap 5 retains the ear 11 in this latching position. As shown in Figs. 3 and 4, the tab 17 is however, through its contact with ear 11, prevented from reaching this position, and, therefore, it projects from the flap 5. This is a useful feature, because it facilitates the unlatching of these parts, that is, the flap 17 may be turned outwardly so that the ear 11 may be raised from its latching position and passed from the wide portion of the aperture 13.

The operation of the folder-easel, thus described, is simple. When the picture 3 is set to a customer, or when it is not to be exhibited, the picture may be protected from dust and the folder may be made to lie flat by folding the flaps 5 and 6 across the front of the picture. If desired a curved slot 21 may be provided in flap 5 in such a location that it may be engaged by the ear 11 when the flaps are in position to protect the pic-

ture. This, however, forms no part of my present invention.

When the picture is being exhibited flap 5 is swung from the face of the picture upon the line 7, and the flap 6 is swung about 8 in a similar manner. Ear 11 is directed against the flap 17 in the embodiment shown in Fig. 2 at a wide portion thereof, as at 18, so as to thrust the flap outwardly permitting the ear 11 to pass through the opening 13 at a point where the walls 14 are widely spaced apart. As soon as the locking walls 12 pass through the opening 13, the natural tendency of the tab 17 to move to the plane of flap 5 causes the flap to push upon ear 11, and move it into the latching position shown in the drawings. Of course, very little force is necessary to do this because of the natural tendency of flap 6 to move downwardly. I have found, however, that the flap 17 materially assists in positioning ear 11, and in holding ear 11 in this locking position until the tab 17 is manually released.

It will be noted that in the preferred embodiment of my invention no extra parts are required, a latch being formed by merely cutting the material of which the flaps 5 and 6 are made.

Having thus described my invention, what I claim as new and desire to secure by Letters Patent is:

In an easel folder made of sheet material, the combination with a front picture carrying member and a pair of flaps formed from the sheet material, of a latch adapted to hold the two flaps in a predetermined relation, said latch comprising an ear formed from the material of one flap, locking walls formed on the ear of greater width than the ear, and a spring tab struck from the other flap with which the ear may cooperate, said spring tab being integral with said flap along one side, and having shoulders spaced from the integral side, and a relatively narrow locking end spaced from the shoulders, whereby the ear may be passed through the flap through an opening left by springing out the tab, the ear being passed across the shoulders as the tab is flexed, the spring of the tab being adapted to force the locking walls of the ear down into the narrow end of the opening thus holding the two flaps in a fixed position.

Signed at Chicago, Illinois, this 18th day of June, 1926.

JOHN BLYTH.
